UNITED STATES PATENT OFFICE.

GEORGE E. SWENSON, OF HASTINGS-UPON-HUDSON, NEW YORK, ASSIGNOR TO THE BARRETT COMPANY, A CORPORATION OF NEW JERSEY.

FLASHING RECEPTACLE AND BRACE.

Application filed August 30, 1920. Serial No. 406,955.

To all whom it may concern:

Be it known that GEORGE E. SWENSON, a citizen of the United States, residing at 63 Southgate Ave., Hastings-upon-Hudson, in the county of Westchester and State of New York, has invented certain new and useful Improvements in Flashing Receptacles and Braces, of which the following is a specification.

10 This invention relates to a flashing receptacle which will be convenient to handle and install and will be adapted to be shipped without injury.

One of the objects of the invention is to 15 produce a flashing receptacle from a thin sheet of suitable material such as metal in such a way that the same may be conveniently installed and will retain its shape.

Another object of the invention is to 20 produce a flashing receptacle that is so braced that there is very little if any danger of the same being distorted or bent out of shape during handling, shipping and installation of the same.

25 Another object is to so install a flashing receptacle of this character in a concrete wall that danger of concrete or other material entering the inside of the receptacle and obstructing the same is eliminated.

30 Another object is to install a flashing receptacle and so brace the same that danger of sagging or becoming displaced will be overcome, and at the same time the concrete in which it is installed will be strengthened 35 and made safer. Other objects and advantages of the invention will be obvious as the description proceeds.

The invention will be understood from the following description taken in connection 40 with the accompanying drawings illustrating an embodiment of the invention in which the same reference characters are used to designate the same parts in the different views.

45 In the drawings,

Fig. 1 is a perspective view of the device.

Fig. 2 is an end view showing the device in course of installation.

50 Fig. 3 is an end view partly broken away showing the device after being installed in a concrete wall.

Reference character R refers to a flashing receptacle that may be made of a thin sheet of material such as iron which sheet is so 55 bent as to have two substantially parallel

walls 1 and 2, a closed end 3, a depending flange 4, and an upturned lip 5. The end 3 and the flange 4 will preferably be in substantially parallel planes and so disposed with respect to the walls 1 and 2 as to form obtuse angles. This is for the purpose of 60 providing a sloping groove or slot between the walls 1 and 2 when the device is installed with the end 3 and flange 4 in a substantially vertical position as is clearly indicated in Fig. 3.

A long brace 6 made of wood or other convenient material is longitudinally disposed in the mouth of the flashing receptacle R and is retained therein and serves as a filler 70 until after the receptacle is installed by slitting the flange 4 at intervals along the lines 7 and 8 and bending the intervening portion 9 upwardly into contact with the face of the brace 6. The brace 6 is so shaped 75 that its outer edge closes the mouth of the receptacle and its sides converge toward each other, thus making a brace which can be easily removed when desired.

The flashing receptacle R is also provided 80 with a plurality of transverse external braces 10, only one of which is shown in Fig. 1, disposed at desirable points when the device is installed. This brace 10 is so shaped that one portion 11 thereof can be placed in contact with the wall 1 and a portion 12 thereof can be placed in contact with the flange 4 while extensions thereof are so disposed as to facilitate installation of the receptacle 85 and retain the brace 10 firmly anchored in 90 the concrete, and also reinforces the concrete. For this purpose an extension 13 with a bent end 14 may be provided as well as a portion 15 connecting with a portion 16 which portion 16 may be in substantially 95 the same plane as the portion 12. A further extension 17 with a bent end 18 may be provided for securing additional anchorage.

The method of installing the device will 100 be obvious from an inspection of Fig. 2. In this figure reference character B represents a wall or form constructed of wood and extending upwardly from the floor or roof deck D. After the wall B is erected the flashing receptacle R is placed at the 105 proper position with its flange 4 and lip 5 in contact with the wall B, the brace 6 being retained in the mouth of the receptacle as indicated. The desired number of external braces 10 are then applied to the re- 110

ceptacle R and fastened to the wall B by nails 19 and 20 which pass through holes 19' and 20' in the brace 10 as indicated. The concrete is then poured around the receptacle R leaving the space between the walls 1 and 2 entirely free as the brace or filler 6 prevents any concrete from entering the receptacle even if the flange 4 and lip 5 do not closely fit the wall B due to any 10 roughness or irregularities. After the concrete hardens the wall or form B is removed, the nails 19 and 20 cut off or bent down, the lips 9 turned downwardly and the brace 6 is removed, thus leaving a clean opening for 15 the roof flashing. The roof flashing 21 may then be installed with a suitable cant strip if desired in the space 22, and suitable cementing material 23 may be applied as indicated.

It is obvious that the receptacle R may be 20 safely shipped and handled with the brace 6 therein as this brace will prevent bending and keep the mouth of the receptacle from being closed. The braces 10 will hold the receptacle R in place while the concrete is 25 being poured and will also reinforce the concrete after the installation of the receptacle R. Heretofore trouble has arisen by the breaking or chipping off of concrete above flashing receptacles, but the upper wall 2 with its upturned lip 5 and the portion 15 of the brace 10 serve to retain the overhanging concrete much better than has heretofore 30 been done.

I claim:

- 35 1. In a flashing form, a sheet of material having a portion bent so as to form a downwardly sloping receptacle and means for retaining a longitudinal brace in said receptacle.
- 40 2. In a flashing form, a sheet of material having a portion bent so as to form a receptacle having substantially parallel sides and means for retaining a brace in said receptacle.
- 45 3. In a flashing form in combination, a sheet of material bent at one place intermediate its edges at an acute angle and at another place at an obtuse angle so as to

form a receptacle and a wedge-shaped longitudinal brace in said receptacle, and means 50 integral with said sheet to retain said brace temporarily in place.

4. In a flashing form, a sheet of material bent at one place intermediate its edges at an acute angle and at another place at an 55 obtuse angle so as to form a receptacle having a depending flange with a portion of said flange disposed to retain a brace in said receptacle.

5. In a flashing form, a sheet of material 60 bent at one place intermediate its edges at an acute angle and at another place at an obtuse angle so as to form a downwardly sloping elongated receptacle having a flange that is slit and a portion thereof bent to retain a longitudinal brace in said receptacle. 65

6. In a flashing receptacle, in combination, a flashing form, a longitudinal brace to prevent said form from collapsing and a transverse brace to prevent said form from sagging. 70

7. In a flashing receptacle, in combination, a flashing form, a longitudinal brace to prevent said form from collapsing and a transverse brace to prevent said form from sagging, and means to retain said longitudinal brace in place while said form is being installed. 75

8. In a flashing receptacle, in combination, a flashing form, a longitudinal brace to prevent said form from collapsing and a transverse brace to prevent said form from sagging, and means to retain said brace in place while said form is being installed. 80

9. In a flashing receptacle, in combination, a flashing form, a longitudinal brace to prevent said form from collapsing and a transverse brace to prevent said form from sagging, and means to retain said braces in place while said form is being installed, said longitudinal brace substantially closing one side of said form and being adapted to be removed after said form has been installed. 85

In testimony whereof I affix my signature.

GEORGE E. SWENSON.
